UNITED STATES PATENT OFFICE.

KELLEY M. TURNER, OF NEW YORK, N. Y., ASSIGNOR TO GENERAL ACOUSTIC COMPANY, A CORPORATION OF NEW YORK.

MULTIPHONE.

No. 893,286.

Specification of Letters Patent.

Patented July 14, 1908.

Application filed December 21, 1905. Serial No. 292,677.

To all whom it may concern:

Be it known that I, KELLEY M. TURNER, a citizen of the United States, residing at New York city, in the county of New York and State of New York, have invented certain new and useful Improvements in Multiphones, of which the following is a full, clear, and exact description.

The object of the invention is to collect all the audible sounds within an auditorium and transmit the same over ordinary telephone wires, and receive them in such a way that the original sounds are reproduced in a second auditorium, so as to be heard and enjoyed by persons within with substantially the same comfort and facility as if they were present in the auditorium or transmitting locality.

With this object in view, my invention consists in the combination, location and arrangement of parts hereinafter described and shown, and finally particularly pointed out in the appended claims.

The drawing illustrates a sound transmission system embodying the principles of my invention.

The ordinary telephone serves to transmit sounds received by it, but with a great reduction in the intensity thereof, so that not only is it necessary to originally direct the sounds closely into the transmitting instrument, but the ear must be closely applied to the receiving instrument in order that the sound may be at all audible. It is evident that the ordinary telephone system is not adapted to be used for reproducing concerts, theatrical performances, and the like, because in these cases it is impossible for the sounds to be closely directed into the transmitting instruments. It is still further impractical on account of the inconvenience of listening to the reproduction through an ordinary receiver applied to the ear, an arrangement which is furthermore expensive, since it necessitates receiving circuits for every person for whom the performance is to be repeated.

By the present invention I overcome the defects and objectionable features above mentioned, and secure a reproduction of all the sounds within the original auditorium at a second point or auditorium where they may be heard and enjoyed by all the persons congregated.

Referring to the drawing, 1 denotes a

transmitting instrument, and while it is possible that different forms of transmitting apparatus can be used, I have in my experiments been able to secure the most satisfactory results with the form of transmitter set forth and shown in Letters Patent No. 874,004 and No. 711,974. This transmitter, 60 comprises a transmitting disk 2, with a series of circumferential openings 3 for the admission of sound. Two of these are assembled within a box, in which is also contained a battery which furnishes the necessary current. This transmitting box is placed at any desired receiving point, preferably upon the stage of the auditorium, and directly behind 70 the foot lights thereof, so as to be concealed from the audience.

5 designates line wires passing through the floor of the stage in any inconspicuous way, and led through a line circuit 6 to the receiving point 7.

At the receiving point 7 I locate what I shall term a multiphone receiver which is arranged and constructed to reproduce the original sounds with sufficient intensity to 80 entirely fill and be heard in a second auditorium of reasonable size. This multiphone receiver consists of a block or casing 8 in the rear of which are inset a plurality of telephone receivers 9, all located in a multiple 85 circuit with the line wires 6.

10 designates channels from the respective telephone receivers all directed into a common chamber 11, which forms the throat of 90 a horn 12 directed into the receiving auditorium.

By the above arrangement all the sounds spoken or produced upon the stage of the auditorium are collected in the transmitting box 1, and transmitted over the line so as to 95 be reproduced in each of the receivers 9. These act in exact concert with one another, being in perfect phase on account of their connection with the same line wire circuit. Inasmuch as the various channels 10 are of 100 equal length and symmetrically placed, the sound passes forward in each with the same speed, so that every wave or vibration arrives at the throat or chamber 11 at precisely the same instant. In this way the articulation and purity of the reproduced 105 sound is perfectly maintained, while at the same time the intensity is augmented in proportion to the number of receivers used, so that the sound can be easily heard through- 110

out a receiving auditorium of any ordinary size.

What I claim is:—

In a multiphone, a pair of transmitters connected in multiple, a horn having a block with convergent passages, a plurality of receivers inset in said passages and connected in a multiple circuit with said transmitters,

said transmitters being included in a box having a battery.

In witness whereof, I subscribe my signature, in the presence of two witnesses.

KELLEY M. TURNER.
